SHOWER HEAD OR SIMILAR ARTICLE

Arthur Anthony Fiorentino, Newark, Del., and Harper Landell, Whitemarsh, Pa., assignors to Speakman Company, Wilmington, Del.

Filed Aug. 13, 1965, Ser. No. 86,687

Term of patent 14 years

(Cl. D91—3)

FIG. 1.

FIG. 2

FIG. 3.

FIG. 4.

FIG. 5.

The characteristic part of the design consists in the sloping bottom rim as shown in FIGS. 2, 3 and 4.

We claim:

The ornamental design for a shower head or similar article, as shown and described.
